ATTORNEY.

UNITED STATES PATENT OFFICE.

EDMUND N. BROWN, OF SAN FRANCISCO, CALIFORNIA.

DESIGN FOR AN ELECTRIC HEATER.

54,889.

Specification for Design.

Patented Apr. 20, 1920.

Application filed August 18, 1919. Serial No. 318,421. Term of patent 14 years.

To all whom it may concern:

Be it known that I, EDMUND N. BROWN, a citizen of the United States, and a resident of San Francisco, county of San Francisco, State of California, have invented a new, original, and ornamental Design for an Electric Heater, of which the following is a specification, reference being had to the accompanying drawings, forming a part thereof.

Figure 1 is a front view of my heater.
Fig. 2 shows a cross section of Fig. 1.

I claim:

The ornamental design of an electric heater substantially as shown.

EDMUND N. BROWN.
